US0D1001224S

(12) United States Design Patent (10) Patent No.: US D1,001,224 S
(45) Date of Patent: * Oct. 10, 2023

(54) GROUND STAKE

(71) Applicant: Eagles Nest Outfitters, Inc., Asheville, NC (US)

(72) Inventors: Peter G. Pinholster, Jr., Asheville, NC (US); Ryan Marc Klinger, Asheville, NC (US); Emily Anne Danielson, Mars Hill, NC (US); Nicholas James Hunt, Asheville, NC (US)

(73) Assignee: Eagles Nest Outfitters, Inc., Asheville, NC (US)

() Term: 15 Years

(21) Appl. No.: 29/816,249

(22) Filed: Nov. 19, 2021

(51) LOC (14) Cl. 21-04

(52) U.S. Cl.

USPC D21/840

(58) Field of Classification Search

USPC D8/1, 349; D21/840; D23/217; 135/118; D11/143, 148, 152, 155
